ATTORNEY

UNITED STATES PATENT OFFICE

CHARLES J. CARTER, OF KANSAS CITY, MISSOURI

GRAIN BIN

Application filed March 8, 1929. Serial No. 345,412.

My invention relates to bins and more particularly to grain bin units of knock-down character adapted to be associated with other units for constructing bins of various sizes, 5 the principal objects of the invention being to facilitate the erection of grain bins, to provide for the use of relatively plentiful and easily obtainable material for the erection of bins, to securely connect the wall members 10 of a bin by means assuring the accurate alignment of wall members and sealing engagement of adjacent wall members, and to provide bin members which may be accurately and securely assembled with relatively 15 small labor and exercise of skill.

In accomplishing these and other objects of the invention, I have provided improved details of structure, the preferred forms of which are illustrated in the accompanying 20 drawing, wherein:

Fig. 1 is a perspective view of a bin constructed in accordance with my invention.

Fig. 2 is an enlarged detail perspective view of end portions of abutting wall strips 25 at a bin corner and illustrating a clamping member inserted in registering kerfs of the strips for connecting the walls.

Fig. 3 is a vertical section of a corner portion of a bin including portions of strips 30 shown in Fig. 2 and similar portions of strips mounted thereon and connected by the upwardly projecting end of the clamp member.

Fig. 4 is a cross section adjacent the upper 35 edge of the strip portions shown in Fig. 2, illustrating the manner in which the clamp binds the end of one strip to the side of an adjacent strip.

Referring in detail to the drawing:

1 designates generally a bin comprising 40 vertical walls differentiated for convenience as a side wall 2 and an end wall 3, and a floor 4, and 5 sills laid on edge for supporting a bin above the surface of the ground, the structure illustrating an example of an enclosure which may be formed by the use 45 of my invention.

I contemplate using boards or strips of 50 uniform length, preferably 2 x 4 lumber six feet long, because of the availability of such

material at relatively low prices, for forming both the floor and walls of the bin, special features such as kerfs formed in boards adapted for use in the walls not interfering with the utility of the boards for use in the 55 floor. The production, distribution, purchase, and installation of the material for the bins are thus greatly simplified, since the strips for floors and walls may be exactly alike, and are more economical when exactly 60 alike.

Strips 6 comprising the floor have grooves or recesses 7 in one longitudinal edge and tongues 8 on the opposite edge adapted to 65 seat in the grooves of adjacent strips, said edges being preferably transversely arcuate and respectively concave and convex for forming the grooves 7 and tongues 8, whereby the strips may be brought into snug engagement with each other to form a relatively sealed and tight floor.

The walls are formed of a plurality of similar strips 9 and the end walls of like strips 10, the two sets of strips being differently 75 designated for convenience in describing the structure, and each having a concave longitudinal lower edge 11 and a convex upper edge 12 whereby one strip may be snugly engaged with and mounted on a lower strip and will be relatively securely latched against 80 sidewise displacement and in alignment therewith.

The tapering crowns of the strips tend to prevent water from moving between adjacent strips, and the taperingly grooved lower 85 edges of superimposed strips provide margins overlapping the upper edges of supporting strips to conduct water past the joint.

End kerfs 13 are provided in the ends of 90 each strip 6, 9 and 10 extending vertically parallel with the vertical corners or arris edges 14 and 15 of the ends, and transverse side kerfs 16 and 17 are formed in the sides 95 of the strips adjacent the ends thereof and spaced from the corners 14 and 15 similarly to the spacing of the end kerfs from said corners. Kerfs in abutting surfaces of adjacent and abutting strips in any relation may be brought into registry to receive a connecting member 18 presently described. A kerf 100

in the side surface of a horizontal side wall member may for example be brought into registry with the end kerf of a horizontal end wall member extending in the same plane 5 as and abutting the side surface of the side wall member at the end thereof, to receive a connecting member.

The bottom strips of the walls are mounted on the floor in abutting relation to form 10 corners, and the clamps 18 are insertable in the upper ends of the registering kerfs to bind the abutting portions of adjacent wall strips together.

The clamp 13 preferably used comprises 15 a key or staple-like nail having a web-like body portion 19 and wing-like tapering flanges or gripping members 20 on each edge of the web at right angles thereto, having sharp edges 21, the web portion being relatively freely movable in the kerfs and the wings being adapted to enter the wood at right angles to the kerfs to latch the opposite wings respectively in the abutting portions of adjacent strips and thus clip or bind 25 the two strips securely together.

The kerfs preferably have sufficient depth so that the outer faces of the wings may have clearance from the bottoms of the kerfs when the clamps are mounted in abutting strips, 30 the wing faces extending laterally right angularly to the webs. I preferably, however, provide clamps having sides diverging downwardly as shown in Fig. 3 so that the upper ends 22 of the clamps are narrower than the 35 spacing of the bottoms of registering kerfs when the abutting strip ends are in snug engagement whereby a clamp being driven into the abutting strips will tend to draw the strips together.

The upper end of each clamp may project above the upper edges of abutting strips to receive the superimposed strips and latchingly engage in the kerfs thereof to connect the superimposed strips with each other and 40 frictionally latch the superimposed strips to the lower strips.

The bin may be provided with a suitable outlet 23 including preferably a door 24 adapted to control the discharging movement of the grain from the bin. A ventilator 25 is also preferably provided at the upper end of the bin and may be formed by cutting out portions 26 of the strips to form an aperture 27 in the side wall, mounting 50 wings 28 on the portions 26 cut from the side wall strips and hinging the ventilator in the opening.

A roof 30 may be mounted on the bin and end wall strips at the upper end of the bin 60 may be tapered to provide for slanting of the roof.

In using the invention for the illustrated purpose, the strips are provided of uniform length having kerfs in their ends and kerfs 65 in each side adjacent the ends. A quantity of

the strips may be supplied for constructing an enclosure of any desired capacity. The first laid wall strips are laid edgewise and are easily adjusted for registry of the kerfs of abutting strips, for example, end kerfs 70 with side kerfs, to receive the clamping members. A superimposed strip is easily and accurately positioned on a laid strip by reason of the specified spacing and depth of the side kerfs of side wall strips and end kerfs of 75 end wall strips, and vice versa.

The walls may be built up to any desired height and will be relatively securely latched and retained to resist strains either from contents or from exterior influence. 80

A clamp may be driven into laterally registering kerfs of horizontally adjacent strips as far as desired for a particular purpose or mode of application, and preferably to provide for the projection of a portion of a clamp 85 beyond an edge of the strip in which it is driven to engage a vertically adjacent strip. A clamp may for example be driven through one strip and into the kerf of a lower strip to connect the upper and lower strips. 90

In countersinking the clamp far enough so that a following clamp may enter the upper strip, I prefer to limit the extent to which the clamp is driven into a strip so that its upper end may project above said strip to receive 95 a superimposed strip.

A bin may comprise a single unit formed of uniformly dimensioned material in which the end edge of an end wall is in abutting relation with the side surface of a side wall 100 adjacent the end thereof.

It is apparent that an enclosure may be formed of any desired dimensions by laying a suitable number of side and end wall strips for a first layer with ends of the strips in 105 abutting relation for registry of kerfs to receive the clamps, the end walls of intermediate adjacent units thereby comprising partitions between the units. Other strips and layers are then superimposed as described. 110

A relatively stable and sealed bin may therefore be constructed without the use of corner posts, studding, or any heavy members, and by boys or unskilled labor.

A structure erected as described may be 115 dismantled with a relatively small amount of labor and substantially no damage or deteriorating effect on the elements. Sections including one or more groups of strips comprising layers of the structure may be stored 120 or transported for re-erection elsewhere. The clamps while effectively latching the strips together when installed may be removed and the strips stored or transported separately from the clamps.

What I claim and desire to secure by Letters Patent is:

1. In a bin of the character described, a side wall including a strip having a vertical kerf in a side surface perpendicular to said 130

surface, an end wall including a strip having a kerf in its end registering with said side wall kerf, and a clamp in said registering kerfs for binding said strips together and 5 projecting vertically from said strips to engage in kerfs in similarly kerfed strips.

2. In a bin of the character described, strips forming side and end walls and having registering kerfs in abutting portions perpendicular to the surfaces of said walls, and 10 including a pair of horizontally abutting strips, a clamp in registering kerfs of said pair of strips to bind the strips together and having an end portion projecting vertically 15 from said pair of strips, and a second pair of horizontal abutting strips in edge abutting relation with said first named pair of strips and having registering kerfs receiving 20 projecting end of the clamp.

3. In a bin of the character described, a side wall including a pair of strips, one superimposed upon the other, an end wall including a similar pair of strips positioned with their ends abutting the sides of the side 25 wall strips adjacent the ends of said side wall strips, the lower strips having registering kerfs including upper portions adapted to receive a clamp, and a clamp in said registering kerfs having wings embedded in the 30 walls of the kerfs to bind said lower strips together and projecting upwardly from the upper surfaces thereof, the upper adjacent strips having registering kerfs aligned respectively with the kerfs in adjacent lower 35 strips, said projecting end of the clamp being engaged in said upper kerfs for enabling the clamp to latch said upper strips together and bind the upper strips to the lower strips.

4. In combination with a side wall strip 40 having a side kerf and an end wall strip having an end kerf registering with the side kerf of said side wall strip, side and end wall strips kerfed similarly to the first named strips and mounted in edge abutting relation 45 on said first named strips with kerfs aligned with kerfs of lower strips, and a single binding member located in said kerfs to hold said strips in assembled relation.

5. In a structure of the character described, a side wall including a plurality of 50 series of horizontal aligned end-abutting strips having registering vertical kerfs in abutting end faces, and aligned vertical kerfs 55 in adjacent side faces, means in registering end face kerfs for retaining aligned abutting strips in end abutting relation, a plurality of transverse walls each including a series of strips having ends abutting in side faces of 60 selected side wall strips and end face kerfs registering with the side face kerfs of adjacent side wall strips to form vertical channels, and means in each of said channels securing the transverse strips to the side wall 65 strips and having portions extending into the

channels of adjacent strips for securing adjacent series of said strips together.

6. A bin including bottom and vertical walls comprising a plurality of similarly formed strips each having identically formed 70 kerfs rectangular in cross section in each end surface on the median line thereof and in each side surface at right angles to the end kerfs and spaced from the end surfaces of the strips, a distance equal to the spacing of said end kerfs from the side surfaces of the strips for selective abutment of strip and registry of kerfs of abutting strips having registering surfaces to form aligned grooves in edge abutting strips and closed channels in 75 end and side abutting strips and provide grooves having parallel side walls and channels having parallel side walls and parallel end walls, and clamps, each comprising a web substantially less in thickness than the width 80 of said kerfs and having width substantially equal to the distance between said channel end walls to move freely into said grooves and channels and pairs of wings on each longitudinal edge of said clamp extending oppositely 85 therefrom a total distance greater than the width of said kerfs and having sharp edges embedded in the side walls of said kerfs to latch the clamp in said grooves and channels.

7. The method of constructing a grain bin or the like composed of strips having registerable grooves in the ends thereof, including arranging a pair of strips in end to end abutting aligned relation to effect registry of said grooves superimposing a second pair of similarly arranged strips on the first named pair of strips with the grooves of the two pairs in alignment, and inserting fastening means in said aligned grooves to secure said strips together. 95

8. The method of constructing grain bins or the like composed of strips having grooved end faces and grooved side faces perpendicular to said end faces, including arranging a pair of strips to effect abutment of selected 100 faces and registry of the grooves in said faces, arranging a second pair of strips in the same relation to each other as the strips of the first named pair, locating the strips of the second named pair in engagement with the 105 similar strips of the first named pair to align grooves in similar strips, effecting engagement of a clamping nail in said grooves to secure the strips of each pair together and secure the second named pair to the first 110 named pair, and limiting the extension of said nail in the grooves of the second named pair to leave portions of said grooves free to receive a nail for attaching a third pair of strips to the second named pair of strips. 115

In testimony whereof I affix my signature.
CHARLES J. CARTER.
